UNITED STATES PATENT OFFICE.

WILLIAM J. DUNCAN, OF WARDNER, IDAHO.

SHAVING-BRUSH.

1,074,497.

Specification of Letters Patent.

Patented Sept. 30, 1913.

Application filed December 6, 1912. Serial No. 735,324.

To all whom it may concern:

Be it known that I, WILLIAM J. DUNCAN, a citizen of the United States, residing at Wardner, in the county of Shoshone and State of Idaho, have invented new and useful Improvements in Shaving-Brushes, of which the following is a specification.

The invention relates to shaving brushes and more particularly to the class of fountain shaving brushes.

The primary object of the invention is the provision of a shaving brush wherein liquid soap may be held so that the same can be fed to the bristles of the brush for the convenient application of the soap to the face of the user when shaving, thus obviating the necessity of a separate holder for the soap, the feed of the liquid soap being readily and easily regulated and the flow thereof shut off when the brush is not in use.

Another object of the invention is the provision of a brush of this character in which the handle thereof is formed with a liquid soap chamber so that liquid soap can be poured into the same whereby it may be permitted to flow into the bristles of the brush for the production of lather on the application of the said brush to the face of the user during shaving.

A further object of the invention is the provision of a brush of this character which is simple in construction, thoroughly reliable and efficient in its purpose, and inexpensive in manufacture.

With these and other objects in view, the invention consists in the construction, combination and arrangement of parts as will be hereinafter more fully described, illustrated in the accompanying drawing, and pointed out in the claim hereunto appended.

In the drawings:—Figure 1 is a side elevation of a brush constructed in accordance with the invention. Fig. 2 is a vertical longitudinal sectional view thereof. Fig. 3 is an end elevation of the ferrule in which the bristles of the brush are mounted, showing the valve or stopper for closing the discharge mouth of the handle of the brush.

Similar reference characters indicate cor-

responding parts throughout the several views in the drawing.

Referring to the drawings by numerals, the brush comprises a hollow handle 5 forming a liquid soap container which is constructed from glass, formed at one end with an externally threaded neck 6 and a flat opposite closed end 7, the neck 6 being detachably engaged in a ferrule 8 having threaded end portions 9 and 10, the portion 9 being engaged with the threaded neck 6 while the opposite end portion 10 has engaged therein a bristle carrying thimble 11 in which are fixed the inner ends of the brush bristles 12.

Arranged within the ferrule 8 and resting upon the neck 6 of the handle 5 is a conical shaped cap 13 formed with a contracted inwardly tapering valve seat 14 for receiving a resilient valve or cork 15 which is fixed centrally upon the thimble 11, the cap being fastened on the neck 6 in any suitable manner. The thimble 11 is formed concentric to the valve or cork 15 with a plurality of discharge openings 16 opening into a frusto-conical shaped delivering nozzle 17, the latter being suitably fixed within the thimble 11 and projects into the bristles 12 at a central point thereof. The handle 5 is filled through the neck 6 thereof with liquid soap, and on the engagement of the thimble 11 in the ferrule 8 and by working the said thimble inwardly the valve or cork 15 will be brought into engagement with the seat 14 in the cap 13, thereby shutting off the flow of the liquid soap from the handle 5 to the bristles through the opening 16 and discharge nozzle 17, and on turning the thimble 11 in the reverse direction the valve or cork 15 will be unseated so that the liquid soap will flow through the cap 13, opening 16, and be discharged through the nozzle 17 into the bristles 12, so that the said soap can be applied to the face of the user of the brush.

From the foregoing it is thought that the construction and manner of operation of the device will be clearly understood, and therefore a more extended explanation has been omitted.

What is claimed is:—

A shaving brush comprising a hollow handle, a ferrule detachably mounted on one end of the handle, a cap mounted in the ferrule and having a valve seat, a perforated thimble adjustably engaging the ferrule, a valve carried by the thimble and engageable in the valve seat, brush bristles mounted in the thimble, and a discharge nozzle com-

municating with the perforations in the thimble and projecting into the brush bristles.

In testimony whereof I affix my signature in presence of two witnesses.

WILLIAM J. DUNCAN.
